UNITED STATES PATENT OFFICE.

PERRY E. MACK, OF MILWAUKEE, WISCONSIN, ASSIGNOR, BY MESNE ASSIGNMENTS, TO BRIGGS & STRATTON CORPORATION, OF MILWAUKEE, WISCONSIN, A CORPORATION OF DELAWARE.

COOLING MEANS FOR GAS ENGINES.

Original application filed October 24, 1921, Serial No. 510,065. Divided and this application filed April 4, 1923. Serial No. 629,812.

This invention has for its object to provide an air cooling system for small stationary gas engines of the type usually employed for driving washing machines and 5 other light machinery.

The invention consists of a blower formed within a fly-wheel by inwardly extending blades co-operating with a stationary disc set into the fly-wheel with a central opening 10 to admit the air to the blades and a peripheral opening in such a location as to direct the blast of air from the blades against the radiating fins along the engine cylinder.

15 An object of the invention is to direct a current of air from the fly wheel against the side of the engine cylinder without creating air currents in other directions and without the use of conduits or nozzles but by merely 20 forming a discharge opening in the stationary cover for the hollow fly wheel at such location as to obtain the air current directed against the side of the engine cylinder.

With the above and other objects in view 25 the invention consists in the gas engine cooling means as herein claimed and all equivalents.

This application constitutes a division of my application for governor and blower for 30 gas engines, Serial No. 510,065, filed October 24, 1921.

Referring to the accompanying drawings, in which like characters of reference indicate the same parts in different views,

35 Fig. 1 is a side elevation of a gas engine constructed in accordance with this invention with the fly-wheel sectioned to show the blower blades thereof, and

40 Fig. 2 is a plan view with the fly-wheel again sectioned.

In these drawings, 10 indicates a gas engine crank case mounted on a base 11, constituting the fuel reservoir and supporting the engine cylinder 12, which, instead of being 45 water jacketed, is provided with projecting fins or ribs 13, which are inclined in the same direction so as to be in line with a current of air created by the blower action of one of the fly-wheels 14.

50 This fly-wheel is keyed on the crank shaft 15 and is overhung to bring the weight of its rim near the vertical plane of the bearing for the crank shaft in the crank case. Inci-

dently this overhanging structure of the fly-wheel is utilized to constitute a housing for containing the governor parts and the blades of the blower fan. Extending inwardly from the rim of the fly-wheel and preferably formed integrally therewith are radial blower blades 16, which, by reason of the rapid rotation of the fly-wheel, tend to create a fan action, causing a current of air to flow from the center of the wheel outwardly. This action is restrained to some extent so as to give direction to the blast of air created by a deflector 17 consisting of a sheet metal plate or disc secured to spacing lugs on the crank case and fitting within the annular flange around the face of the fly-wheel. Air is free to enter through the central opening of the air deflector or blast director, but its outlet is confined to the single opening 18 at the edge of the deflector, which is so positioned as to direct the current of air against the cylinder in line with the ribs 13.

In operation the rapid rotation of the blower blades 16 causes them to act as fans drawing air through the central opening of stationary plate 17 and expelling it through the opening 18, which is so positioned as to direct the blast in line with the inclined radiating fins around the engine cylinder to most conveniently cool the same. This is accomplished without having to set the fly-wheel away from the crank shaft bearing to accommodate a blower fan for the fly-wheel itself constitutes the fan and the stationary deflector plate confines the air against discharge in directions that would not serve the purpose and directs the entire blast against the ribbed walls of the cylinder. In this manner the cooling of the engine cylinder is accomplished economically and efficiently.

What I claim as new and desire to secure by Letters Patent is:—

1. In a gas engine fly-wheel, fan blades within the rim portion thereof, and a stationary deflector plate fitting within the rim portion of the fly-wheel and having an opening through which the current of air caused by the rotating fan blades is directed against the cylinder of the engine.

2. In a gas engine having a cylinder crank case and a fly-wheel having a hollow face next the crank case, fan blades within

- the hollow face of the fly-wheel, a deflector plate mounted on the crank case and fitting within the rim of the fly wheel, with an opening through which the current of air created by the rotating fan blades is directed against the engine cylinder, and heat radiating ribs on the engine cylinder inclined in the direction of the current of air from said opening.
6. In a gas engine, a disc secured to the crank case and spaced therefrom to provide an air passage between them, said disc having a central opening through which the engine crank shaft passes, and an overhung fly-wheel on the crank shaft fitting around the disk and provided with fan blades, said disc having an opening near its edge through which said fan blades discharge the air which they draw through the central opening of the disc and said opening in the edge of the disc being so located as to direct the current of air against the wall of the engine cylinder.
10. 3. In a gas engine, a disc secured to the crank case and spaced therefrom to provide an air passage between them, said disc having a central opening through which the engine crank shaft passes, and an overhung fly-wheel on the crank shaft fitting around the disk and provided with fan blades, said disc having an opening near its edge through which said fan blades discharge the air which they draw through the central opening of the disc and said opening in the edge of the disc being so located as to direct the current of air against the wall of the engine cylinder.
15. 4. In a gas engine, a hollow fly-wheel, fan blades within the fly-wheel, a stationary plate closing the hollow of the fly-wheel with a central opening for admitting air to the hollow of the fly-wheel and a peripheral opening in position to direct the current of air induced by the fan blades toward the cylinder of the engine.
20. 5. In a gas engine, a hollow fly-wheel, fan blades within the fly-wheel, and a stationary plate fitted to the hollow face of the fly-wheel and the fan blades so as to prevent the escape of air held by centrifugal force in
- the spaces between the fan blades but provided with an opening for releasing the air only at such a position that it will be directed against the engine cylinder.
25. 6. In a gas engine, a hollow fly-wheel, fan blades therein, a stationary plate fitting against the hollow face of the fly-wheel and the fan blades to prevent the escape of air carried by centrifugal force between said fan blades, there being a central opening in the plate for admitting air to the interior of the fly-wheel, and a peripheral opening in the plate at that portion thereof where the fan blades move toward the engine cylinder for permitting the escape of the air while directed toward the engine cylinder.
30. 7. In a gas engine, a hollow fly wheel having one face closed, a stationary metal disk fitting against the open face of the fly wheel and provided with an opening through which is discharged an unconfined but directed current of air induced by the rotation of the fly wheel, and an engine cylinder in the path of the air current.
35. 8. In a gas engine, a hollow fly wheel having one face closed, fan blades within the fly wheel, a stationary metal disk fitting within the open face of the fly wheel and provided with an opening through which is discharged an unconfined but directed current of air induced by the rotation of the fly wheel, and an engine cylinder in the path of the air current with streamline radiating fins.

In testimony whereof, I affix my signature.
PERRY E. MACK.
